UNITED STATES PATENT OFFICE

100,482

DESIGN FOR A SINKER

Walter L. Tripp, Chillicothe, Ohio

Application May 1, 1936, Serial No. 62,410

Term of patent 14 years

To all whom it may concern:

Be it known that I, Walter L. Tripp, a citizen of the United States, residing at Chillicothe, in the county of Ross and State of Ohio, have invented a new, original, and ornamental Design for a Sinker, of which the following is a specification, reference being had to the accompanying drawing, forming part thereof.

I claim:

The ornamental design for a sinker as shown.

WALTER L. TRIPP.
